UNITED STATES PATENT OFFICE.

EDWARD STAHL, OF PRESCOTT, ARIZONA TERRITORY.

METHOD OF AND DEVICE FOR FITTING GARMENTS.

SPECIFICATION forming part of Letters Patent No. 376,558, dated January 17, 1888.

Application filed June 4, 1887. Serial No. 240,268. (No model.)

To all whom it may concern:

Be it known that I, EDWARD STAHL, of Prescott, in the county of Yavapai, and Territory of Arizona, have invented a new and Improved Method of and Device for Cutting Garments, of which the following is a full, clear, and exact description.

Reference is to be had to the accompanying drawings, forming a part of this specification, in which similar letters of reference indicate corresponding parts in all the figures.

Figure 1 is a front elevation of the flexible band to compass the bust. Fig. 2 is a similar view of the opposite surface of the said band. Fig. 3 represents the waist strap. Fig. 4 represents the neck-strap or collar. Fig. 5 is a perspective view of one of the sliding clips upon the bust-band. Fig. 6 is a sectional view of the bust-strap on the line xx of Fig. 1. Fig. 7 is a diagram showing certain lines upon the form. Fig. 8 shows the method of attaching the pattern material to the bust-band. Fig. 9 shows the bust-band and pattern material applied, and Fig. 10 illustrates the method of cutting the pattern material.

The object of this invention is to provide means whereby any person may cut and fit ladies' dresses and other garments and always obtain a good-fitting body or waist; and the invention will first be described in connection with the drawings, and then pointed out in the claims.

The device consists of three principal parts: the bust-band A, the waistband B, and the neckband C.

A is a pliable metallic band about an inch wide, and of sufficient length to more than reach once entirely around the largest portion of a lady's bust. Fig. 1 represents what may be called the "outer side" of the band, and shows that it is crossed laterally by numbered graduating-lines b , and that a line of small holes, c , runs through its longitudinal center. Fig. 2 shows its inner side and exhibits two stationary loops, a a' , and two sliding clips, b b' . (Represented more clearly in Fig. 5.) Upon the band A is also placed the loose or sliding loop d .

The waist-strap B is made of any suitable material—such as cloth, leather, or some other material. It is graduated by lateral numbered

lines e e , and has a buckle, e' , at one end, and a few holes, e^2 , at the other. It is about one-half inch wide and long enough to reach a little more than once around a person's waist. 55

The collar C is made of cloth or some other suitable material. It is provided on one end with a buckle, f , and on the other with a few holes, f' . It is also graduated with transverse lines f^2 , and is of a length to reach a little more than once around a person's neck.

A very little reflection will show that, if we take a model of a lady's bust and draw upon it certain lines, like the dotted lines h on the diagram, Fig. 7, then cut pieces of cloth exactly 65 like the shape of what is shown between the lines, when these pieces are joined at the edges they must make a closely-fitting garment. Since we cannot, however, have an exact model of every person, let us attempt the same upon 70 the person's self who is to wear the garment. Here we encounter difficulties, principal among which are, first, to find two lines—one upon the front and one upon the back—which shall be exactly in the middle of, or which divide 75 into two equal parts, the surface of that part of the person which is to be covered by the garment. This is necessary, as the pieces constituting the garment have to be in pairs, each of which must be of like shape. The second difficulty is in holding or fastening upon 80 the person the piece or pieces of stuff in such a manner that slight motions of the person will not disarrange one piece while the next one is being cut. These difficulties are overcome by this invention in the following manner, viz:

First, a piece of strong paper or other material, D, Fig. 8, suitable for patterns of a size somewhat more than enough to make one-half 90 of the garment is taken and a straight horizontal line drawn upon it in such a manner that when it is laid upon the person the portion above the line will reach from under the arm to the neck, and the other from just below the arm down as far as the garment is to reach. Then this piece of material D is sewed or fastened upon the metal band A, as illustrated in Fig. 8, so that the line upon the stuff is just over the holes c of the band, commencing at the zero end of the latter with one edge of the stuff and letting it run as far as it may 95 100

upon the band. Now the upper portion of the material D will be doubled downward and the band is placed about the person's bust just below the arms. The end *i* is shoved through the loops *a' a'* upon the opposite end of the band, and when sufficiently tight the end is fastened by means of the little hooks *j* and the movable loop *d*. The band is then drawn around so that the zero-point thereof is just in line with the line of the person's breast, and held there in place by pieces of twine *k* being passed through the eyes *k'* of the sliding clips *b'* and tied around the shoulders.

Next the waist-strap B and the throat collar C are buckled upon the person, so that the zero-point of each shall also be in the middle line of the person's breast, as illustrated in Fig. 9. Now the zero-points of the three parts A, B, and C having been brought exactly into the middle front line of the person, by dividing the numbers indicated on A, B, and C (being the whole measure of circumference of bust, waist, and throat) by two, the middle line of the back of the person is established.

Next make a straight cut upward through that portion of the piece of stuff D fastened to the band A, which is turned downward at a place just where the cut will meet the armpit. This will form two parts, which can be turned upward. Each can be held separately over the person in such a manner that it will lie smoothly over the form and can easily be cut so that the edges *l m* will meet, the armhole-line being indicated by the twine *k*, which holds up the band A and the throat-line indicated by the lower edge of the collar C.

Next the portion of stuff below the arms, which has till now hung loosely, is cut, as shown at *o p q r* in Fig. 10, and trimmed in a manner that when the edges of the several pieces are brought close together the two edges *n n'* touch the front and back middle lines of

the person. They will also lie closely on the form. After this the band A is removed from the form, and will then have an appearance somewhat like that illustrated in Fig. 10. Now the pieces *o', p', q',* and *r'* are removed from the band and used as patterns for cutting the cloth, allowance being made for seams.

By the prevailing custom of cutting garments from measures it is by merest chance that a garment will fit the first time the pieces are put together, even though the cutting were done by the most experienced cutter, and in a less experienced hand it proves in most cases a very difficult matter to cut a well-fitting garment, while an inexperienced hand can do next to nothing in the way of cutting a garment by that system.

By this invention no measures are taken, so and the most inexperienced person can cut a set of patterns to accurately fit any form.

Having thus fully described my invention, I claim as new and desire to secure by Letters Patent—

1. The method herein described of cutting garments, which consists in applying pattern material to a bust-band and forming a down-fold in the material, and applying the band and material to the bust of the person just beneath the arms, and then cutting the down-fold to fit over the shoulder, and then cutting the material below the band to fit the waist, substantially as described.

2. The bust-band A, graduated upon one surface and provided with a series of holes, *c*, in combination with two sliding clips, *b'*, having opposite eyes *k' k'* at the edges, and provided with the fastening-cords *k*, substantially as described.

EDWARD STAHL.
